REFLEX LENS

Robert I. Nagel, Skokie, Ill., assignor to Elastic Stop Nut Corporation of America, Union, N. J., a corporation of New Jersey

Application August 3, 1955, Serial No. 37,307

Term of patent 14 years

(Cl. D48—32)

Fig. 1 is an elevational view of a reflex lens embodying my invention; and

Fig. 2 is a sectional view taken on line 2—2 of Fig. 1. The ornamentation shown in Fig. 1 is continuous around the entire lens.

I claim:

The ornamental design for a reflex lens, as shown and described.
